UNITED STATES PATENT OFFICE

2,433,785

STOVE

Herbert M. Reeves, Kankakee, Ill., assignor to
Florence Stove Company, Gardner, Mass., a
corporation of Massachusetts

Application January 8, 1944, Serial No. 517,531

4 Claims. (Cl. 126—214)

1

The invention relates to stoves and more particularly to kerosene stoves of the so-called portable type.

One object of the invention is to increase the convenience and utility of stoves of the above general character by extending the cooking top to provide more working space thereon and by providing means for effectually covering the cooking top and burners when the stove is not in use.

Another object is to provide an extension top and cover structure for portable kerosene stoves in the form of a simple, inexpensive unit capable of being quickly and easily installed.

Other objects and advantages of the invention will become apparent from the following detailed description of the preferred embodiment illustrated in the accompanying drawing in which:

Figure 1 is a perspective view of a stove equipped with an extension top and cover structure embodying the features of the invention.

Fig. 2 is a rear view of the stove.

Fig. 3 is a fragmentary transverse sectional view of the extension top and cover structure installed on a stove.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For purposes of illustration, the invention has been shown as applied to a floor type portable kerosene cooking stove. As shown in the drawing, the stove comprises a body including a generally rectangular cooking top 5 supported at each corner by angle iron legs 6. A shelf 7 secured to the legs 6 below the cooking top cooperates with the latter to define a compartment for a plurality of burners 8, there being three such burners in the exemplary stove. The burner compartment is closed at the back and sides by a back wall 9 and side walls 10 in the form of sheet metal panels spot welded or otherwise rigidly secured to the legs 6. Liquid fuel such as kerosene is supplied to the burners 8 in well-known manner from a reservoir 11 supported at one side of the stove body.

In stoves of the type disclosed, the burners 8 are usually arranged in a single row. The cook-

2

ing top 5 is accordingly constructed as an elongated narrow top section, usually of sheet metal, having a depending flange 12 around its entire periphery to which the legs 6 are secured. The top section is provided with a row of holes for the burners 8 over which are placed the usual removable grids 13. A splash plate or back guard 14 in the form of a flanged sheet metal panel is commonly supplied with the stove. Usually the guard is removably attached by stove bolts 17 to the flange 12 along the rear edge of the cooking top as shown in broken lines in Fig. 3.

In carrying out the invention, I provide an auxiliary or extension top adapted to be installed at the rear of the stove structure flush with the upper surface of the cooking top 5 thereby greatly increasing the working space available on the top of the stove. The extension top is preferably of sheet metal construction and as herein shown comprises a flat generally rectangular member 15 having an integral depending flange 16 extending around its entire periphery. Suitably spaced holes are provided in the front and rear flanges 16 so that the extension top may be removably secured as by the stove bolts 17 to the cooking top 5 in place of the back guard 14, while the latter may be similarly secured to the rear flange of the top member 15.

Suitable braces 20 are provided at each end 30 of the top member 15 to hold it rigid. The braces are preferably in the form of flat metal straps each having a straight upper leg and an angularly inclined lower leg. The upper leg is adapted to be secured to the flange 16 at one side of the top member and adjacent the rear edge thereof as by stove bolts or the like. The end portion of the lower leg is twisted through an angle of 90° and bent down as indicated at 21 to lie flush against the stove leg 6. The braces 20 may be anchored to the stove legs in any suitable manner, as for example, by sheet metal screws 22.

The braces 20 additionally provide pivotal support for a swinging cover 25 adapted to be closed 45 down over both the extension top and the cooking top 5 of the stove. For this purpose the upper leg of each brace is extended above the upper surface of the extension top as indicated at 26.

50 The cover 25, as herein shown, comprises a flat, generally rectangular member of substantially the same width as the extension top 15 and having an integral flange 27 around its entire periphery. Stove bolts 27' inserted through the flanges 55 27 at opposite sides of the member and through

the extensions 26 of the braces 20 permit the cover to swing between the open and closed positions shown respectively in solid and broken lines in Fig. 1. In the closed position, the top member is substantially horizontal and adapted to lie closely adjacent the cooking top 5 so as to effectually cover the burner grids 13. Moreover, it provides a clear, flat working surface and may conveniently serve as a table. The back guard 14 is adapted to act as a stop for holding the cover in the open position as shown in Fig. 3.

While the extension top and cover structure may be installed at the factory when the stove is initially assembled, it lends itself readily to packaging and shipment as a unit for installation in existing stoves. When supplied as a unit, it includes the top member 15, the cover member 25, a pair of braces 20 and the necessary screws and bolts. Installation is extremely simple as it is only necessary to bolt the top member to the cooking top in place of the back guard 14, the latter in turn being bolted to the rear flange of the top member. For securing the braces to the stove legs, small holes may be drilled therein for the accommodation of the screws 22.

It will be apparent from the foregoing that the invention provides means whereby the cooking top of a portable kerosene stove may be effectually extended to provide greater working space on the top of the stove. Through the provision of a swinging cover, the top of the stove may be effectually closed when not in use, thus enhancing its appearance and providing a clear surface adapted to serve efficiently as a table or the like. The extension top and cover structure is simple in construction and inexpensive to manufacture. As it is extremely easy to install and lends itself to packaging as a unit, it is particularly well suited for application to existing stoves.

I claim as my invention:

1. An extension top and cover structure for a stove having a body including a generally rectangular cooking top, said structure comprising, in combination, a sheet metal top member adapted to be removably secured to the cooking top along its rear edge, braces secured to opposite sides of said top member and adapted to be anchored to the stove body below the top member to hold the member rigid, said braces having extensions projecting above the upper surface of the top member, a cover member dimensioned to extend over the top member and the cooking top of the stove, and means supporting said cover member on the extensions of said braces for swinging movement between open and closed positions.

2. An extension top and cover structure for a stove having a body including a generally rectangular cooking top with a back guard removably secured at its rear edge, said structure comprising, in combination, a rectangular top member of sheet metal adapted to be secured to the cooking top in place of said back guard, braces secured to opposite sides of the top member adjacent its rear edge and adapted to be anchored

to the stove body below the top member to hold the member rigid, the upper ends of said braces extending above the upper surface of said top member, a cover member dimensioned to extend over said top member and the cooking top of the stove, and means supporting said cover on the extended ends of said braces to swing between an upright open position and a closed position closely adjacent the cooking top of the stove, said back guard being attached to the rear edge of said cover member and acting as a stop to hold the cover member in the open position.

3. The combination with a stove having a body including a generally rectangular flanged sheet metal cooking top, of an extension top comprising a flat generally rectangular sheet metal member having an integral flange along its front edge adapted to be removably secured in face-to-face relation to the flange at the rear edge of the cooking top, metal straps removably secured to opposite sides of the extension top and to the stove body below the cooking top to hold the extension top rigid, a depending integral flange extending along the rear edge of said member, and a backguard removably secured to said last mentioned flange and projecting upwardly above the surface of the extension top.

4. In a cook stove, in combination, a stove body including supporting means and a top structure extending a substantial distance rearwardly of the supporting means, a pair of braces extending upwardly from said supporting means along the sides and adjacent the rear edge of said top structure, said braces being rigidly connected to the top structure and projecting above the surface thereof, and a cover member pivotally supported on the projecting portions of said braces and dimensioned to extend over substantially the entire area of said top structure when in closed position.

HERBERT M. REEVES.
